US00D468589S

(12) **United States Design Patent** (10) Patent No.: **US D468,589 S**
 Bulcher et al. (45) Date of Patent: ** Jan. 14, 2003

(54) **PLATE HAVING CONDIMENT WELLS**

(75) Inventors: **David J. Bulcher**, Powell, OH (US);
Matthew A. McCurdy, Marysville, OH (US); **Christina M. Tranfaglia**, Glenview, IL (US)

(73) Assignee: **Pactiv Corporation**, Lake Forest, IL (US)

(**) Term: **14 Years**

(21) Appl. No.: **29/141,202**

(22) Filed: **May 1, 2001**

(51) LOC (7) Cl. **07-01**

(52) U.S. Cl. **D7/553.1; D7/555**

(58) **Field of Search** D7/500, 505, 506, D7/550.1, 551.1, 551.3, 553.1, 553.4, 553.5, 553.6, 553.7, 553.8, 554.1, 554.2, 555; D9/341; 206/557, 561, 562, 563, 564; 220/23.8, 23.83, 500, 507, 512, 556, 574, 575, 738, 904

(57) **CLAIM**

The ornamental design for a plate having condiment wells, as shown.

DESCRIPTION

FIG. 1 is a perspective view of a plate having condiment wells;

FIG. 2 is a top view of a plate having condiment wells;

FIG. 3 is a bottom view of a plate having condiment wells;

FIG. 4 is a right-side view of a plate having condiment wells;

FIG. 5 is a left-side view of a plate having condiment wells;

FIG. 6 is a back-side view of plate having condiment wells;

and,

FIG. 7 is a front-side view of a plate having condiment wells.

1 Claim, 3 Drawing Sheets
